UNITED STATES PATENT OFFICE

WALTER LARKIN, OF NORRISTOWN, PENNSYLVANIA, ASSIGNOR TO FIDELITY MACHINE COMPANY, OF WILMINGTON, DELAWARE, A CORPORATION OF DELAWARE

CIRCULAR-KNIT RIBBED FABRIC

Application filed March 27, 1926. Serial No. 97,891.

The principal object of my invention is to produce circular knit ribbed fabric having an artistic design interknit therewith.

The design produced, in accordance with 5 the principles of my invention, is capable of practically unlimited variation as to pattern and color.

The machine employed in producing my improved fabric is a circular rib knitting machine of special design and construction, forming the subject of a separate application for patent Serial No. 181,507, filed April 10 6, 1927, which is an improvement over my prior United States Patent No. 1,624,792, dated April 12, 1927.

My invention is not limited to any particular class of goods but may be adapted to any article of manufacture which can be directly or indirectly produced on the above type machine, including hosiery, neck wear, gloves, 20 or any straight tubing which may be split or cut into shapes of any desired form.

In the accompanying drawing:

Fig. 1 illustrates diagrammatically one of 25 the simplest forms of design, utilizing a series of horizontal stripes and a series of interrupted vertical stripes as applied to a folded top of a stocking; and

Fig. 2 illustrates diagrammatically the 30 process of producing the simple form of design illustrated in Fig. 1.

Figs. 3 to 5 inclusive are diagrams of a few of the designs I may employ in my improved fabric.

Referring to Fig. 2 of the drawing, the foundation of the fabric comprises regular horizontal courses of stitches 1, 1, which in the aggregate comprise vertical outside wales 2, 2 alternating with inside wales 3, 3.

In a design comprising horizontal and vertical stripes I prefer to form the horizontal stripes by changing the knitting yarn from 40 one color to another and I also prefer to use the knotting method of yarn splice in order to obtain a clean cut line of demarcation between adjacent stripes.

The vertical stripes I prefer to form by the plating method and it will be obvious 45 that the horizontal stripes, either in complete, 50 interrupted or partial form may be pro-

duced by this method also, on a suitably colored foundation.

As shown in Fig. 2 the uppermost course of stitches 1 and a portion of the next lower 55 adjacent course are of one color (blue) indicated at 4, and being knotted as at 5 to a different colored thread (red) indicated at 6. The thread 6 in turn is knotted at 7 to a thread of a third different color (green) indicated at 8, and this thread is subsequently 60 knotted at 9 to another differently colored or a white thread as indicated at 10.

There is no regular sequence of colors necessary, the desired color for the particular portion of the design at hand being selected 65 from the series and "run" to the knitting needles.

The vertical stripes, as above stated, are plated on the stitches forming the cylinder 70 wales 2, 2 by threads of any desired color or colors and may run the entire length of the respective wale as indicated at 11, 11, or they may be interrupted as indicated at 12 for the purpose of forming a design, the thread between the plated stitches being permitted to 75 float on the inside face of the fabric as indicated at 13.

From the above description, which covers the simpler adaptations of my invention it will be apparent that I may form a foundation fabric of a single color or of any desired 80 multi-colored striped variations and in addition thereto I may interpose upon the outside wales of such foundation fabric any desired variety of vertical stripes in the form of 85 plated stitches.

I have chosen the circular ribbed fabric as a foundation for reason of its elasticity and have selected the outside wales thereof to support the plated design, running the 90 plating threads walewise of the fabric, in order that this elastic quality of the fabric can be maintained.

From the simpler form of the invention shown in Figs. 1 and 2 and described hereinabove the formation of patterned designs may be developed through the slightly complicated symmetrical designs shown in Figs. 95 3, 4 and 5 to the most complicated art designs, by the proper color selection and 100

proper manipulation of the foundation threads in combination with the properly selected colored plating threads and their proper manipulation.

5 In some instances the plating threads, of the various colors employed, each extend parallel with a certain single and predetermined wale 2, but in designs of the tapestry class which are especially adaptable to high grade 10 neck wear, the plating threads are not each confined to any single wale but may be moved from one wale to another as required in forming such designs, this class of goods is produced on a machine of the above mentioned 15 type but of a more complicated nature, which is to form the basis of another application for patent. If desired each and every stitch of each and every outside wale may have superposed thereon a plating thread of desired color which would entirely cover the 20 face of the foundation fabric.

Having clearly illustrated various forms 25 of designs which may be produced on my improved fabric and having clearly described the manner in which they are produced, I do not intend that the scope of the invention be limited to the designs shown as anyone 30 familiar with the art can upon reference to the body of the specification in which the above descriptions appear, formulate designs of their own pattern without departing from the features of my invention.

What I claim is:

1. A new article of manufacture comprising 35 tubular knit ribbed fabric having inside and outside wales and a design formed on the said outside wales and composed of a plurality of different independent threads respectively plated on successive immediately 40 adjacent outside wales.

2. A new article of manufacture comprising 45 tubular knit ribbed fabric having inside and outside wales and a design formed on the said outside wales and composed of a plurality of different independent threads respectively plated on successive immediately adjacent outside wales, said design having an outline disposed at an angle with respect to said wales.

3. A new article of manufacture comprising 50 tubular knit ribbed fabric having inside and outside wales and a design formed on the said outside wales and composed of a plurality of different independent threads respectively plated on successive immediately adjacent outside wales, said design having an outline of which a portion is disposed at an angle with respect to said wales.

4. A new article of manufacture comprising 55 tubular knit ribbed fabric having inside and outside wales and a design formed on the said outside wales and composed of a plurality of different independent threads respectively plated on successive immediately adjacent outside wales, said design having

an outline of which a portion is disposed at an angle with respect to said wales, and another portion is disposed parallel to said wales.

5. A new article of manufacture comprising 60 tubular knit ribbed fabric having inside and outside wales and a design formed on the said outside wales and composed of a plurality of different independent threads respectively plated on successive immediately 65 adjacent outside wales, said design having an outline of which a portion is disposed at an angle with respect to said wales, and another portion is perpendicular to said wales.

6. A new article of manufacture comprising 70 tubular knit ribbed fabric having inside and outside wales and a design formed on the said outside wales and composed of a plurality of different independent threads respectively plated on successive immediately 75 adjacent outside wales, said design having an outline of which a portion is disposed at an angle with respect to said wales, another portion is disposed parallel to said wales, and another portion is disposed perpendicular to 80 said wales.

7. A new article of manufacture, comprising 85 a tubular knit ribbed fabric formed of a continuous foundation thread which is composed of a plurality of individual lengths of 90 differently colored threads knotted together end to end in selective succession and knitted into a plurality of courses of foundation 95 stitches thereby forming the said tubular knit ribbed fabric, said fabric having inside and 100 outside wales, said fabric also having a design depicted on its outer face, said design being formed in part by a plurality of different independent threads respectively plated on successive immediately adjacent 105 outside wales, and in part by the differently colored courses of stitches of the foundation fabric, the said plating threads being adapted 110 in color and position to coordinate with the adjacent suitably colored foundation 115 stitches to complete the said design on the said outer face of the fabric.

8. A new article of manufacture, comprising 120 a tubular knit ribbed fabric formed of a continuous foundation thread which is composed of a plurality of individual lengths of 125 differently colored threads knotted together end to end in selective succession and knitted into a plurality of courses of foundation 130 stitches thereby forming the said tubular knit ribbed fabric, said fabric having inside and outside wales, said fabric also having a design depicted on its outer face, said design being formed in part by a plurality of different independent threads respectively plated on successive immediately adjacent outside wales, and in part by the differently colored courses of stitches of the foundation fabric, the said plating threads being adapted in 135 color and position to coordinate with the ad-

jacent suitably colored foundation stitches to complete the said design on the said outer face of the fabric, and the outline of said design become disposed, in part, at an angle with respect to said outside wales.

5 9. A new article of manufacture comprising tubular knit ribbed fabric having inside and outside wales and a solid design formed on the said outside wales and composed of 10 a plurality of different independent threads respectively plated on successive immediately adjacent outside wales.

15 10. A new article of manufacture comprising tubular knit ribbed fabric having inside and outside wales and a design formed on the said outside wales and composed of a 20 plurality of different independent threads plated on said outside wales to form a plurality of parallel stripes of different lengths, the ends of said stripes defining at least a part of the outline of said design.

25 11. A new article of manufacture comprising tubular knit ribbed fabric having inside and outside wales and a design formed on the said outside wales and composed of a 30 plurality of different independent threads plated on said outside wales to form a plurality of parallel strips of different lengths, the ends of said strips defining at least a part of the outline of said design, and at least a portion of that part of the outline which is defined by said stripe ends being disposed at an angle with respect to the wales.
